UNITED STATES PATENT OFFICE.

CHARLES EDWARD HAVILAND, OF LIMOGES, FRANCE.

DESIGN FOR A COVER-DISH.

SPECIFICATION forming part of Design No. 28,929, dated June 28, 1898.

Application filed June 1, 1898. Serial No. 682,308. Term of patent 7 years.

To all whom it may concern:

Be it known that I, CHARLES EDWARD HAVILAND, a citizen of the United States, residing at the city of Limoges, in the Republic of France, have invented and produced a new and original Design for a Cover-Dish or Similar Article, of which the following is a specification, reference being had to the accompanying drawings, forming part thereof, and in

10 which—

Figure 1 is a top view of a cover-dish bearing and incorporating my design. Fig. 2 is a side elevation of same, and Fig. 3 is a vertical section through a portion of same on the 15 dotted line 3 3 of Fig. 1.

The leading features of my design consist of the ornamental form and configuration of the dish and its cover, substantially as illustrated in the accompanying drawings.

20 In the drawings, A designates the body of the dish, and B the cover therefor, the said cover having the raised ornamental central portion C, bearing the handle D. The rim of the cover B has a scalloped edge and bears 25 the ornamental band comprising the scroll-figures E, the scroll-figures F, which at their center have the appearance of being con-

nected to the scroll-figures E, and the scroll-figures G, which are intermediate the ends of the said figures E F.

30

The sides of the body A are of ornate configuration and comprise the upper section II and lower section I, the latter curving downward and inward on graceful lines to the ornamental base J.

35

The upper edges of the sides of the body A bear the ornamental band K, corresponding with the ornamental band along the edges of the cover B, and along the line separating the upper and lower sections II I of said sides are 40 the ornate scroll-decorations L, extending on scalloped lines entirely around the dish.

At opposite ends of the body A are handles M M.

What I claim is—

45

The design for a cover-dish or similar article, substantially as shown and described.

Signed at New York, in the county and State of New York, this 31st day of May, A. D. 1898.

CHARLES EDWARD HAVILAND.
